UNITED STATES PATENT OFFICE

142,521

DESIGN FOR A GOLF TEE

Joseph William Hughes, Southgate, London,
England

Application March 21, 1945, Serial No. 118,608
In Great Britain February 14, 1945

Term of patent 14 years

(Cl. D34—5)

To all whom it may concern:

Be it known that I, Joseph William Hughes, a subject of the King of Great Britain, residing at Hartlands, Chaseside, Southgate, London, N. 14, England, have invented a new, original, and ornamental Design for a Golf Tee, of which the following is a specification, reference being had to the accompanying drawing, forming part thereof.

I claim:

The ornamental design for a golf tee, substantially as shown.

JOSEPH WILLIAM HUGHES.
